UNITED STATES PATENT OFFICE.

MARIE S. FEDERMAN, OF NEW YORK, N. Y.

SNAP-FASTENER.

1,217,164.

Specification of Letters Patent. Patented Feb. 27, 1917.

Application filed February 7, 1916. Serial No. 76,534.

To all whom it may concern:

Be it known that I, MARIE S. FEDERMAN, a citizen of the United States of America, residing at New York city, county and State 5 of New York, have invented certain new and useful Improvements in Snap-Fasteners, of which the following is a full, clear, and exact description.

This invention relates to improvements in snap-fasteners for gloves, garments or the like, the object being to provide an inexpensive but effective fastener of this variety. To accomplish this result I employ a socket-member and a button-member arranged to interlock one with the other, special fastening means being provided to maintain said members in interlocked relationship.

I will now proceed to describe my invention in detail, the essential features of which will be summarized in the appended claim, reference being had to the accompanying drawing, forming part hereof, wherein—

25 Figure 1 is a sectional view of my improved fastener;

Fig. 2 is a sectional plan view enlarged, of the socket-member, the section being taken on a line 2—2 in Fig. 1; and

30 Fig. 3 is a top plan view of the socket-member illustrating the locking element before it is pressed into place.

As herein illustrated, my invention comprises a socket-member 1 and a coöperating button member 2 arranged to be engaged by the socket-member, as shown in Fig. 1. The button-member 2 consists of a base 3 and a rounded head 4 having a rounded shank 5 of less diameter than the head to form an 35 annular recess. The round-headed shank is adapted to be forced into the pocket 6 of the socket-member 1 and to be retained therein by a locking element 7.

The locking element 7 is held in slots 8 cut into the wall of the pocket 6 and consists of a yieldable oblong shaped ring or loop which is originally circular as shown in Fig. 3, and pressed into the slots 8, the pressing action changing the shape of the ring from circular to oblong, and at the same time pressing the sides 9, 9 of the ring inwardly as at 9^a to form ridges. The ring is preferably in one piece in order that the ac-

tion of forcing the head 4 into the pocket will spring the ring or loop intermediate its 55 ends and not at its ends, which would be the case if the ring was not in one piece or joined at the ends thereof.

The locking ring 7 is not secured in any way, but remains in the slots 8 by reason of 60 the fact that it is pressed into said slots, the ridges 9^a at their corners providing stops or shoulders 10 (Fig. 2), whereby a locking action is produced by virtue of the shape of the ring. The above described fastener is 65 a very cheap yet effective device.

When the head 4 is forced into the pocket, the side members of the ring will be spread apart but will assume their normal position as soon as the said head has been forced entirely therebetween. The button-member will finally come to rest with the side-members of the ring engaging the reduced portion 5 of the head of the button.

The circular locking element 7 is of thin 75 slightly resilient flexible metal, adapted at all points to be forced in through said slots of the socket by a suitable tool, forming ridges 9^a, which will engage the material of the pocket at the ends of the slots and hold 80 their position within said pocket on each side of the neck of the button member and in the path of insertion and withdrawal of said button head, permitting it to pass through said ridges on insertion so that they 85 will fit in behind it and lock it in place. The deformed locking shape of said ring (shown in Fig. 2) is quite different from its normal shape displayed in Fig. 3. I have no need of a special irregular construction 90 in the first place. A simple circular ring is easily obtained and fulfils the conditions stated if made of material which will yield for the production of the ridges 9^a, but permit them to hold their position by engagement with the material at the ends of the slots.

Having now described my invention, what I claim and desire to secure by Letters Patent is:

In a snap fastener, a socket member adapted to receive the head of a button member and having a socket pocket provided with slots, in combination with an endless ring of slight resiliency, any portion 105 of said ring being adapted to be forced in-

wardly through said slots into the path of movement of a button head entering or leaving said pocket, the inwardly projecting portions being held in position by the slight resiliency of the ring and adapted to yield sufficiently to the inward pressure of a head, though tending to obstruct its withdrawal.

5 Copies of this patent may be obtained for five cents each, by addressing the "Commissioner of Patents, Washington, D. C."

Signed at New York city, N. Y., this 3rd day of February, 1916.

MARIE S. FEDERMAN.
